UNITED STATES PATENT OFFICE.

EMILE GIRARDEAU AND JOSEPH BETHENOD, OF PARIS, FRANCE.

RADIOTELEGRAPHY.

1,245,702.

Specification of Letters Patent.

Patented Nov. 6, 1917.

Application filed July 26, 1916. Serial No. 111,446.

To all whom it may concern:

Be it known that we, EMILE GIRARDEAU and JOSEPH BETHENOD, both citizens of the French Republic, residing at 10 Rue Auber, Paris, in the Republic of France, have invented certain new and useful Improvements in Radiotelegraphy, of which the following is a specification.

This invention relates to the construction of multiple spark gaps, such as are used for the production of oscillations by "impulse" in radio-telegraphy.

Professor Wien was the first to show in 1906, that in order to bring about excitation by impulse of an oscillating circuit it is advisable to use multiple spark gaps with very close metallic electrodes and a number of spark gaps proportioned to the tension brought into play. The impulse effect being in general the more accentuated according as the partial sparking distances are smaller, the great importance of reducing them as far as possible is evident, in view of the distinctness of the phenomenon and of the output.

Various methods have been suggested and used for the construction of such spark gaps, but those hitherto laid down generally lead to excessive heating, either in consequence of the discharge of the sparks in a closed vessel or in consequence of the shape of the electrodes, which is not favorable to the continual displacement of the sparks on the surface of the electrodes.

The method of construction forming the subject of the present invention greatly facilitates the cooling, at the same time considerably simplifying the construction itself.

Figure 1, annexed to this specification, shows a first example of the application thereof. In this figure A is a plain or hollow cylinder of hard metal, on which are threaded rings of insulating material B; on the latter the electrodes properly so called fit with gentle friction, and a mica washer D of very accurately gaged thickness, is arranged between two consecutive rings B; and finally the electrodes C are constituted in the form of disks comprising a hub E

and a double swelling F, the axial thickness 50 of which is equal to that of the hub E and of the ring B. In this way the sparking distance between two consecutive electrodes is equal to the gaged thickness of the washers D, and the spark discharges between the 55 swellings F opposite the two consecutive electrodes, the external diameter of the washers D being sufficiently great to prevent any sparking between two adjacent hubs. As the adjustment of the various parts is 60 easy, and may be effected with very great precision, it being assumed that one is only concerned with turned parts, the exact parallelism of the electrodes is insured, and the spark runs constantly over the active surface of the electrodes.

In order to insure the cooling of the electrodes, which is indispensable to the satisfactory working of the spark gap, the latter terminate in vanes G; in addition to which 70 they are pierced with several holes H, thanks to which the air inclosed between two electrodes can circulate and be continually renewed.

The ribs G serve at the same time for the 75 collection of current, suitable terminals O and O' enabling a larger or smaller number of spark gaps to be brought into operation.

For very powerful stations the spark gap that we have just described may of course be 80 utilized, but it is advisable to insure by mechanical means the compulsory rotation of the spark, for the slightest stoppage of the latter may then cause local consumption of the electrodes, which is exceedingly harmful 85 to the satisfactory working of the spark gap. It is to this end that the method of construction represented by way of example in Fig. 2 corresponds.

In this spark gap half the electrodes are 90 fixed and the other half are movable. A metallic frame L supports the fixed electrodes C'. They are in the form of rims and carry two swellings F', which constitute the active surfaces. These electrodes are provided with vanes G to insure the cooling thereof, and are insulated from one another by washers of mica (or other insulating ma-

terial) indicated at D' of gaged thickness. They are then pressed against one another by any suitable locking device.

The mounting of the movable electrodes 5 is exactly the same as that shown in Fig. 1. The movable electrodes are supported by a shaft A, on which are fitted the insulating rings B. On the latter are fixed with gentle friction the electrodes C, which are insulated 10 from one another by mica washers D. Up to this point, therefore, the construction is absolutely identical with that of Fig. 1. The outer part of the electrodes is slightly modified. It carries two swellings F, which are 15 placed opposite the swellings F' of the movable electrodes.

The shaft A may be rotated by a system of gearing R controlled by a pulley N, which makes the whole system rotate about the axis 20 X X' and at the same time makes the shaft A rotate about the axis Y Y'. In this way the points of discharge of the sparks are continually renewed, and consequently the cooling of the electrodes is effectually secured.

25 Fig. 3 shows the arrangement in plan, in order to indicate better the relative positions of the electrodes and their rotary movements.

Modifications of detail may of course be 30 made in the method of construction forming the subject of this patent without altering the essential principle of the invention. Thus the shape of the electrodes may be modified. The number of electrodes is of course optional, and may be anything whatever.

35 What we claim and desire to secure by Letters Patent in the United States, is:—

1. In an electric spark gap, the combination 40 of a plurality of movable electrodes provided with registering apparatus to permit of the flow of air currents through the entire set of electrodes on a line parallel to the axis thereof.

2. An electric spark gap comprising a 45 plurality of disks forming electrodes provided with a plurality of transverse apertures to permit of the flow of air through the entire set of disks parallel to the axis thereof, and means to allow of air circulating 50 through and between adjacent disks.

3. In an electric spark gap, a circular electrode, having a circular reduced portion concentric with its axis, and means to permit of the transverse passage of air through the 55 reduced portion of the electrode.

4. In an electric spark gap, an electrode comprising a circular boss, a circular ring of bulbous cross section, means connecting said boss and ring, an annular space formed 60 in the external periphery of and extending to near the center of said bulbous part and means to allow of air circulating axially of said connecting means.

5. In an electric spark gap, the combination 65 of a plurality of fixed electrodes, a plurality of rotatable electrodes provided with radiating vanes and means in the rotatable electrodes adjacent the vanes to permit the flow of air through the entire set of rotatable electrodes.

6. In an electric spark gap, the combination 75 of a plurality of fixed electrodes, a plurality of rotatable electrodes, means to rotate said latter electrodes about the axis of the fixed electrodes and means within the rotatable electrodes to permit of the flow of air through the entire set of rotatable electrodes.

7. In an electric spark, the combination 80 of a plurality of fixed electrodes, a plurality of movable electrodes, means to rotate said latter electrodes about the axis of the fixed electrodes, means to rotate said movable electrodes on their own axis and means within the rotatable electrodes to permit of air 85 circulating through the entire set of rotatable electrodes.

8. In an electric spark gap, the combination 90 of a plurality of fixed electrodes, a plurality of movable electrodes, means to rotate said movable electrodes simultaneously about two axes and means to permit of air circulating axially through the entire set of rotatable electrodes.

9. In an electric spark gap, the combination 95 of a plurality of fixed electrodes, a plurality of movable electrodes, means to rotate said movable electrodes simultaneously about two axes and means projecting from the rotatable electrodes to facilitate heat radiations therefrom.

10. In an electric spark gap, the combination 100 of a plurality of fixed electrodes, a plurality of movable electrodes each comprising a circular boss, a circular ring of bulbous cross section, means connecting bulbous part and circular ring, an annular space formed in the exterior of said bulbous part and extending to near the center of said bulbous 110 part and means to rotate the movable electrodes simultaneously about two axes.

11. In an electric spark gap, the combination 115 of stationary electrodes, rotatable electrodes, ribs on the outer periphery of said rotatable electrodes and means to rotate said rotatable electrodes simultaneously about two axes.

12. In an electric spark gap, the combination 120 of stationary electrodes comprising a plurality of disks spaced apart by insulating washers, an annular space interior of each of said disks, means to facilitate heat radiations therefrom, a plurality of rotatable electrodes having annular spaces staggeredly arranged with respect to the interior annular spaces of the fixed electrodes and

means to rotate said rotatable electrodes simultaneously on their own axis and about the axis of the fixed electrodes.

13. In an electric spark gap, the combination of fixed electrodes, rotatable electrodes and supports for both said fixed and rotatable electrodes, gearing between the rotatable electrodes and fixed electrodes, means to support the rotatable electrodes from the

support of the fixed electrodes and means to rotate said rotatable electrodes.

In testimony whereof we affix our signatures in presence of two witnesses.

EMILE GIRARDEAU.
JOSEPH BETHENOD.
